[57] CLAIM

The ornamental design for a lacing element for footwear, as shown and described.

DESCRIPTION

FIG. 1 is a top view of a lacing element for footwear according to the present invention, the bottom view being a mirror image of that shown;

FIG. 2 is a side view thereof;

FIG. 3 is a front view thereof;

FIG. 4 is a rear view thereof; and,

FIG. 5 is a top view thereof.

The broken line showing of a shoe in FIG. 5 is for illustrative purposes only and forms no part of the claimed design.
